BAFFLE FOR STRAIGHT TUBE BOILERS

James F. Kavanagh, Calumet City, Ill., assignor
to The Superheater Company, New York,
N. Y.

Application February 2, 1932. Serial No. 590,361

2 Claims. (Cl. 122—478)

My invention relates to baffles for boilers of the straight horizontal water tube type and more particularly for boilers of such type having superheaters associated therewith.

- 5 A well-known type of boiler comprises generating tubes slightly inclined to the horizontal and extending in planes substantially at right angles to the axis of the steam and water drum together with means for completing the thermal circulation from said drum through said tubes and back to the drum. It is well known also to provide baffling for such boilers whereby the gases make a plurality of passes through the generating tubes. The baffling for such boilers 10 has been a considerable item both as to first cost and maintenance. This is particularly the case where the baffling extends outside the bank of generating tubes, which is necessary in boilers having three gas passes.
- 20 It is the principal object of my invention to provide a baffling arrangement for horizontal straight tube boilers which shall be relatively cheap to make and install as well as to maintain. The superheater for such boilers has often 25 been located above the bank of generating tubes at the point of connection between an up-pass and a down-pass. In such arrangements the ends of the elements of the superheater usually extend through the baffling so as to place the headers in the cooler gases of a second up-pass. This further increases the upkeep of the portion 30 of the baffling which extends above the bank of generating tubes due to the expansion and contraction of the superheater elements.
- 35 It is another object of my invention to provide a baffling arrangement having reinforcement therein of an economical character and having a low upkeep, while adapted to withstand the stresses due to any pipe elements which may 40 pass therethrough.

The novel features of my invention are pointed out in the appended claims. In order, however, that the invention itself may be fully and clearly understood, I will now describe in detail, by way 45 of example and in connection with the accompanying drawing, a boiler in accordance with my invention selected from a number of possible embodiments thereof. In the drawing,

50 Fig. 1 is a sectional elevation of the upper part of a boiler in accordance with my invention.

Fig. 2 is a fragmentary sectional view taken on the line 2—2 of Fig. 1 in the direction of the arrows.

Referring to the drawing more in detail, 10 is a steam and water drum of a boiler having 55 a bank of generating tubes 12—12, the lower portion of which is omitted. For providing a thermal circulation from drum 10 through tubes 12 and back to the drum, I have illustrated an arrangement including downcomer means comprising nipples 14 and headers 16, said nipples connecting the lower portion of drum 10 to the upper ends of headers 16. The lower ends of tubes 12 connect into the headers 16 and the upper ends of tubes 12 connect into uptake headers 18. The upper ends of headers 18 are connected to drum 10 by circulator nipples 20, 20 in the usual manner.

For directing the heating gases through the tube bank having generating tubes 12, I have 70 illustrated baffling means including baffle portions 22 and 24 of refractory material. Baffle portion 22 separates an up-pass 26 from a down-pass 28, passes 26 and 28 connecting through a chamber 30 above the bank of tubes 12 and above 75 upper end of baffle 22. Baffle 24 separates the down-pass 28 from an up-pass 32, passes 28 and 32 being connected at their lower ends at a point not shown. Pass 32, however, extends above the bank 12 to the level of the nipples 80 20 so that the gases pass out to the up-take alongside the drum 10. The baffle of which member 24 is a part extends up to the level of nipples 20.

In accordance with my invention, the baffle of 85 which member 24 is a part is extended upwardly from the upper end of member 24 by baffling means including water tubes 34, 34. Tubes 34 are arranged so that they have a thermal circulation 90 therethru and in order to provide for such circulation I have shown them as connected at one end into the headers 16 just above the upper row of tubes 12. Tubes 34 extend from the headers 16 substantially parallel to the tubes 12 for only 95 a lesser portion of the length of tubes 12, tubes 34 bending sharply upward adjacent the baffle member 24 so as to form an upward extension of the baffle of which member 24 is a part. At their upper ends, tubes 34 connect into the drum 10 so as to complete the path for the circulation of 100

water through such tubes and, in the arrangement shown, tubes 34 may be united to the circulator nipples 20 so as to deliver into drum 10 through such nipples. This arrangement reduces 5 the number of joints necessary in the drum 10, but I do not limit myself to this. As shown, nipples 20 are interrupted intermediate their lengths to receive header members 36, 36 into which the tubes 20 and 34 are rolled so that members 36 10 act as T's or Y's to unite tubes 34 with tubes 20.

The chamber 30 forms a convenient place for 15 a superheater and I have illustrated a superheater 38 in such a chamber. It is preferred, however, that the headers 40, 40 for superheater 20 tubes 38 be in the pass 32 on the opposite side of tubes 34 from the chamber 30. The heating surface 25 of superheater 38 is substantially all in the chamber 30 so as to take advantage of the higher temperature of the gases in such chamber while the headers lie in the gases having a minimum temperature. The tubes 34, however, are set sufficiently far apart so that the elements of the superheater 38 may be readily extended between such tubes so as to connect with the headers, as shown in Figs. 1 and 2.

The tubes 34 serve as a support for refractory 30 or other suitable material 42 which fills the intervals between such tubes and cooperates with tubes 34 in extending baffle 24 up to the level of tubes 20. Such filling material therefore is maintained at substantially the steam temperature of the boiler and is largely protected against the more severe variations in temperature which occur in the heating gases from the furnace. The baffle 24 above the bank of generating tubes 12 is thereby protected from deteriorating at as high a rate as otherwise would be the case. As the baffle 40 portion 22 and the lower part of baffle portion 24

are necessarily protected in large measure by the tubes 12, the provision of the tubes 34 eliminates a large proportion of the deterioration in the baffling in boilers of the horizontal water tube type. Also, the extension of baffle portion 24 by tubes 34 is a relatively economical way of running such baffling upward through the gas space above the bank of generating tubes.

What I claim is:

1. A boiler of the type having a bank of horizontally inclined straight generating tubes, a steam and water drum, means for connecting the ends of said tubes to said drum to complete the circulation therethru, baffling arranged to provide up and down passes for gases thru said bank, said baffling including tubes extending at a sharp angle upward away from said generating tubes, means for causing a thermal circulation thru the tubes in said baffling, and a superheater having headers lying on one side of the tubes in the baffling and its heating surface on the other side thereof. 85

2. A superheater boiler of the type having horizontally inclined straight generating tubes, a steam and water drum, downcomers arranged to connect said drum to the lower ends of said tubes, risers and substantially horizontal circulators arranged to connect the upper ends of said tubes to said drum, additional tubes above and substantially parallel to said generating tubes at the lower ends of the latter for a portion of their length, said additional tubes branching off sharply from said generating tubes and having a connection with said circulators and having also a connection with said downcomers, baffling material on said additional tubes for forming a baffle therewith. 90 105 110 115
